UNITED STATES PATENT OFFICE

JOHN A. PEDERSEN, OF BROOKLYN, NEW YORK, ASSIGNOR TO JOHN A. ROEBLING'S SONS COMPANY, OF TRENTON, NEW JERSEY, A CORPORATION OF NEW JERSEY

CABLE CUTTING AND SKINNING TOOL

Application filed December 10, 1930. Serial No. 501,313.

In electric power and telephone work it is an ever present necessity to remove a portion of the insulation of electrical conductors for the purpose of making connections. At 5 present this work is done mostly with knives of more or less modified form. It requires a great amount of experience and attention to do a good job with such knives, and as a consequence the copper wire inside an electrical 10 conductor is often damaged, many times to such an extent that it breaks after the device wired with such a damaged cable has been in use for some time.

The present invention has for its purpose 15 the provision of a skinning tool having a cut of adjustable depth. Furthermore, the device under discussion is provided with adjustable guides which assure a cut which is parallel to the axis of the wire inside a conductor or cable.

With the above and other objects in view, the invention consists of the novel features of construction, combination and arrangement of parts, hereinafter fully described, 25 claimed and illustrated in the accompanying drawing forming part of this specification, in which similar characters of reference indicate corresponding parts in all views, and in which:

30 Figure 1 is a top elevational, Figure 2 is a cross sectional, partly side elevational, and Figure 3 is a front elevational view. The foregoing views correspond to one another, and show my device in the act of removing 35 the insulation of a cable.

The principal parts of my device and their functions will be understood from the following description:

10 is a cable the insulation of which is just 40 being partially removed. To perform the said operation the lower end 11 of the adjustable cutter 12 is ground to a knife edge, and is brought into cutting contact with the insulation of the cable to be skinned, as shown 45 on Figures 2 and 3. The adjustable cutter 12 is housed in a handle 13 which is substantially a hollow cylinder, provided with an upper tapped portion 14 which engages with the similarly threaded upper portion of the 50 adjustable cutter 12. The locknut 15 is pro-

vided to prevent any accidental change in the adjustment of the adjustable cutter 12. One terminal of the hollow handle provides a seat, through which the cutting terminal 11 projects, for movably engaging the cable 55 skin (Fig. 2).

The amount by which the knife edge 11 protrudes from the handle 13 can be easily adjusted so as to correspond to the thickness of the insulation of the cable or conductor 60 to be skinned. Since the knife edge 11 can penetrate into the cable only the distance by which the said knife edge protrudes from the handle 13, damage to the copper wires inside the cable is effectively prevented. Pin 22 is 65 disposed in a correspondingly shaped slot in the adjustable cutter 12 for the purpose of effecting rotation and proper adjustment of the said cutter.

The lower outer portion of the handle 13 70 is screw-threaded, and by this means the handle is fastened to the lower part or housing of the device, on which there are mounted two guide bars 16 and 16', constructed integrally with racks 17 and 17'. The said 75 racks 17 and 17' are moved in or outward by means of worms 18 and 18' which are rotatively supported in brackets 19 and 19' of said housing. A hollow portion 20 is provided in each of the said brackets 19 and 19' 80 for the purpose of guiding and supporting the racks 17 and 17'. Suitable apertures are provided in the housing for the worm nuts 18, 18', as shown.

As shown on Figure 2, the guide bars 16 85 and 16' straddle the cable to be skinned, thereby assuring parallelism of the cut with the axis of the cable, no matter how hurriedly the operation is performed, or unskilled the operator may be. In addition, the device 90 illustrated possesses a safety feature, since the cutting edge cannot slide off the cable, and the guide bars 16 and 16' prevent the knife edge 11 from cutting into the operator's arm under any condition.

95 My device is adapted not only for cutting the insulation of a cable parallel to the axis of such cable, but also at right angles to it. This latter operation which has to be performed in order to confine the extent of re-

- removed insulation can be effected by turning the adjustable cutter or blade 12 into a position at right angle to said axis, as shown in Figures 2, 3 and 4 and then rotating the tool a full circle around the cable, with the adjustable cutter 12 in cutting contact with the insulation. For longitudinal cutting, said blade is disposed in parallel relation with the axis of the cable.
- 10 While I have shown and described the preferred embodiment of my invention, it is to be understood that many minor modifications may be resorted to within the scope of the invention, and I do not, therefore, desire to be limited to the precise construction illustrated in the drawing.

Having thus fully described my invention, what I claim as new and desire to protect by Letters Patent of the United States is:

20 I claim:

1. A cable skinning tool, having an adjustable cutter and a handle; a lower guiding part provided with movable guides; the separation between the said guides being capable of adjustment, and means for regulating the said separation so as to correspond to the diameter of the cable or insulated conductor to be skinned, the said means consisting of a worm and rack suitably mounted on the said lower guiding part and guide respectively.
2. A cable skin cutting tool comprising a hollow handle having a seat for movably engaging a cable skin, a knife having a cutting terminal projecting from the hollow of said handle at its seat, and means for guiding said terminal during movement of said seat, said means having opposed brackets on said handle at its seat, each of said brackets having therein an aperture, a rackbar disposed in each aperture, arms depending from and rigid with said bars for adjustably engaging opposed portions of a skin, and worm nuts revolvably disposed in said apertures and meshing with said respective bars for adjusting said arms.

Signed at Brooklyn in the county of Kings and State of New York, this 19th day of November, A. D. 1930.

JOHN A. PEDERSEN.
